US0D1095454S

(12) **United States Design Patent** (10) **Patent No.:** **US D1,095,454 S**
(45) **Date of Patent:** **** Sep. 30, 2025**

(54) **DATA CABLE**

(71) Applicant: **Luxshare Precision Industry(Chuzhou), Ltd.**, Chuzhou (CN)

(72) Inventors: **Yujie Xie**, Chuzhou (CN); **Shun Wang**, Chuzhou (CN); **Changming Du**, Chuzhou (CN); **Huaizhou Liu**, Chuzhou (CN)

(73) Assignee: **Luxshare Precision Industry (Chuzhou), Ltd.**, Chuzhou (CN)

(**) Term: **15 Years**

(21) Appl. No.: **29/895,051**

(22) Filed: **Jun. 16, 2023**

(30) **Foreign Application Priority Data**

Mar. 21, 2023 (CN) 202330134568.2

(51) **LOC (15) Cl.** **13-03**

(52) **U.S. Cl.** ..... **USPC** **D13/153**

(58) **Field of Classification Search**

USPC D13/153, 133, 151, 154, 147; D14/433
CPC .. H01R 13/03; H01R 13/7175; H01R 13/514;
H01Q 1/46

See application file for complete search history.

(57) **CLAIM**

The ornamental design for a data cable, as shown and described.

DESCRIPTION

FIG. 1 is a front, bottom and left side perspective view of a data cable showing our new design;
FIG. 2 is a rear, top and right side perspective view of a data cable;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the data cable that form no part of the claimed design.

1 Claim, 8 Drawing Sheets
